ATTORNEYS.

UNITED STATES PATENT OFFICE.

DAVID WALKER, OF NEWARK, NEW JERSEY.

DESIGN FOR A STAIR-CARPET FASTENER.

SPECIFICATION forming part of Design No. 30,723, dated May 9, 1899.

Application filed April 12, 1899. Serial No. 712,809. Term of patent 7 years.

To all whom it may concern:

Be it known that I, DAVID WALKER, a citizen of the United States, residing at Newark, in the county of Essex and State of New Jersey, have invented and produced a new and original Design for a Stair-Carpet Fastener; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front elevation of a stair-carpet fastener of my new design, and Fig. 2 is a section of the same on line *x*.

The leading or material feature of my new design consists in a stair-carpet fastener having the configuration as follows, to wit:

The fastener is in cross-section of quadran-

tal shape, and the outer convex face *a* is for its middle portion bounded by straight side lines *b*. At each end of the central straight portion the convex face gently tapers concavely 25 toward the opposite ends of the fastener, said concavely-tapering portions being bounded by the concave lateral edges *c*. Beyond said concavely-tapering parts the convex face of the fastener tapers more sharply, first concavely and then convexly, providing ogee-shaped tips *d* for the fastener.

What I claim as new is—

The design for a stair-carpet fastener as herein shown and described.

In testimony that I claim the foregoing I have hereunto set my hand this 11th day of April, 1899.

DAVID WALKER.
